UNITED STATES PATENT OFFICE.

LELA M. HOOK, OF IOLA, KANSAS.

PICTURE-HANGER.

1,149,141.

Specification of Letters Patent.

Patented Aug. 3, 1915.

Application filed November 8, 1913. Serial No. 799,976.

To all whom it may concern:

Be it known that I, LELA M. Hook, a citizen of the United States, residing at Iola, in the county of Allen and State of Kansas, 5 have invented new and useful Improvements in Picture-Hangers, of which the following is a specification.

This invention relates to picture hangers and has for its primary object the provision 10 of a device of this character whereby the picture will be firmly supported in vertical position against the wall.

In carrying out my invention it is my purpose to provide mating fastening elements 15 mounted respectively upon the frame and the wall and coöperating to hold the frame in a true vertical position, and the provision of such elements which will facilitate the operation of hanging the frame.

20 A further object of the invention is the provision of a means for effecting an operative application of the wall engaging elements and for preventing said elements from being injured during the attaching 25 operation.

With these and other objects in view which will appear as the nature of the invention is better understood, the invention consists in the specific construction and combination of parts which will hereinafter be 30 more fully described and particularly pointed out in the appended claim.

In the drawing forming a portion of this specification and in which like numerals of 35 reference indicate similar parts in the several views, Figure 1 is a fragmentary sectional view of the picture frame showing the same as supported upon the wall with my improved fastening device. Fig. 2 is a rear 40 view of the frame showing the socket members secured thereto. Fig. 3 is a detail perspective view of one of the socket members. Fig. 4 is a detail perspective view of one of the ball members. Fig. 5 is a detail perspective view 45 of the protector ring. Fig. 6 is a side elevation of one of the ball members with the protector ring applied thereto. Fig. 7 is a view of a modified form of the ball member. Fig. 8 is a sectional view 50 through the socket member taken on line 8-8 of Fig. 3. Fig. 9 is a face view of the socket member.

Referring to the drawing by numerals, 1 designates the picture frame into which the 55 socket members 2 are fastened. Each of the

socket members as shown comprises a screw threaded shank 3 formed at one end with a socket 4 which has its outer edge rolled back to provide an annular hollow rim 5. The said rim is provided at diametrically 60 opposite points with grooves 6 for the reception of a screw driver by means of which the said socket members are screwed into the rear face of the picture frame preferably one into each of the four corners 65 thereof. Arranged within the sockets 4 and connected in any suitable manner to the opposite sides thereof, are oppositely bowed springs 7 which as shown in one embodiment of the invention as having their free 70 ends extended through suitable openings in the sides of the sockets and bearing against the rim 5 of the rolled back edge. These springs coöperate with the spherical head or ball 8 of the members 9 in a manner 75 hereinafter described for the purpose of retaining the mating members operatively associated.

The members 9 are adapted to be driven into the wall at proper points so that the 80 spherical heads or balls 8 thereof will be received by the sockets 4. The spherical heads 8 are formed integrally with the heads 10 of the members 9 and connected therewith by the reduced portion 11 forming the neck 85 12. The heads 10 are adapted to lie flush with the wall while the sockets 4 are arranged to lie flush with the rear surface of the frame so that when the spherical heads of the members 9 are inserted within the 90 sockets 4 the springs 7 snap into engagement with the neck 12 rearwardly of the spherical head, thus providing a firm connection between the parts whereby the picture frame is firmly supported in true vertical 95 position against the wall. While I prefer the members 9 being made in the form of a nail and adapted to be driven into the wall, the said members may be made in the form of a screw as shown in Fig. 7 and in 100 which case the spherical head or ball 8 of the said members is provided with a suitable groove 13 for the reception of a screw driver so that the said members may be screwed into the wall.

With a view of protecting the spherical head or balls 8 from being flattened or otherwise injured while driving the members into the wall, I provide a protector ring 14 which is to be temporarily placed 110

over the head or ball 8 of the members and bear against the head 15 thereof. After the member has been driven into the wall the ring is then removed.

5 From the foregoing description taken in connection with the accompanying drawing it will be manifest that I have provided a device by means of which pictures are firmly supported in true vertical position against 10 the wall, thus preventing any movement of the picture upon the wall due to vibration of the latter under various conditions. It will be further understood that the fastener may be made in different sizes to accommodate 15 date large and small pictures, and that the picture may be readily and quickly hung upon and removed from the wall when desired.

While I have shown and described the 20 preferred form of my invention, it is to be understood that I am not to be limited to the precise construction herein shown, as various changes may be made within the scope of the appended claims without sacrificing any of the advantages of my invention. 25

What I claim is:—

In a picture hanger, a headed shank adapted to be fastened in the wall with its head lying flush therewith, a convex extension projecting centrally from said head and connected thereto by a reduced neck portion, a concave socket member having an integral shank and adapted to be fastened by means of its shank within the picture frame 30 flush with the rear face thereof, whereby said frame, when said convex extension is positioned in said socket, will be supported against forward tilting movement, said socket member having a rolled back edge 35 defining a channel, and oppositely bowed springs arranged in the channel and projecting into said socket for engagement with the reduced neck portion when the parts are operatively associated. 40

45 In testimony whereof I affix my signature in presence of two witnesses.

LELA M. HOOK.
